[57] CLAIM

The ornamental design for a container with lid, as shown and described.

DESCRIPTION

FIG. 1 is a top and side perspective view of a first embodiment of a container with lid, showing my new design, the shading indicating contour only and not being a feature of the design;

FIG. 2 is a side elevational view of a second embodiment thereof;

FIG. 3 is a side elevational view of a third embodiment thereof;

FIG. 4 is a side elevational view of a fourth embodiment thereof;

FIG. 5 is an enlarged elevational view of a fragment thereof encircled in FIG. 4;

FIG. 6 is a side elevational view of a fifth embodiment thereof;

FIG. 7 is a bottom plan view of the container of FIG. 6, the bottom plan view of all the containers being identical, and all the containers being figures of revolution about a vertical axis, apart from the projections on the bottoms thereof;

FIG. 8 is a side elevational view of a lid for a set of containers according to the invention;

FIG. 9 is a view similar to FIG. 8 but rotated 90° about a vertical axis;

FIG. 10 is a top plan view taken from the top of FIG. 8; and, FIG. 11 is a view similar to FIG. 6 but with the container rotated 90° about a vertical axis.

The lid is the same for all the containers.

The difference between FIG. 1 and the alternate embodiments is the varying sizes. The lid is shown separately in FIGS. 8-11 for clarity of illustration.
